UNITED STATES PATENT OFFICE.

CHARLES T. CARLSON, OF CANTON, OHIO.

DESIGN FOR A DISHPAN.

Application filed December 1, 1924. Serial No. 11,548. Term of patent 14 years.

To all whom it may concern:

Be it known that I, CHARLES T. CARLSON, showing my new design; and a citizen of the United States, residing at Canton, in the county of Stark and State of Ohio, have invented a new, original, and ornamental Design for Dishpans, of which the following is a specification, reference being had to the accompanying drawing, forming part thereof.

Fig. 2, a perspective view of the dish pan.

I claim:—

The ornamental design for a dishpan, as shown.

CHARLES T. CARLSON.
